UNITED STATES PATENT OFFICE.

ARTHUR TREVOR DAWSON AND GEORGE THOMAS BUCKHAM, OF WESTMINSTER, LONDON, ENGLAND, ASSIGNORS TO VICKERS SONS & MAXIM, LIMITED, OF LONDON, ENGLAND.

GUN CARRIAGE OR MOUNTING.

No. 926,551.

Specification of Letters Patent.

Patented June 29, 1909.

Application filed September 27, 1906. Serial No. 336,423.

To all whom it may concern:

Be it known that we, ARTHUR TREVOR DAWSON, lieutenant of the Royal Navy, director and superintendent of Ordnance Works, and GEORGE THOMAS BUCKHAM, engineer, both subjects of the King of Great Britain, residing at 32 Victoria street, Westminster, in the county of London, England, have invented certain new and useful Improvements Relating to Gun Carriages or Mountings, of which the following is a specification.

This invention relates to gun carriages or mountings particularly those of the kind that are employed for short guns and in which great stability is required, as in mountain-gun carriages.

According to our invention the recoiling gun-cradle comprises two long sliding pieces or skids which are laterally arranged with respect to the casing of the recoil buffer and return springs and which are adapted to slide on guides with which the said casing is furnished, the arrangement being such as to reduce the bending stresses in the cradle to the smallest degree. The said buffer and spring casing has a depending pivot-pin supported by a traversing bar or frame provided at its forward part with bosses which are bored out to fit the axle-tree. The gun is moved laterally around the axis of the depending pivot-pin by means of traversing gear carried by the said traversing bar or frame, and is moved vertically around the axis of its trunnions by means of elevating gear carried by the trail.

In order that our said invention may be clearly understood and readily carried into practice we will describe the same more fully with reference to the accompanying drawings, in which:

Figure 1 is a side elevation of a gun and its mounting or carriage constructed in accordance with our invention. Figs. 2 and 2^a are respectively a detail plan and a partial transverse sectional elevation of the bracket by which the forward part of the gun is supported on the skids. Fig. 3 is a side elevation of a portion of the carriage or mounting drawn on a somewhat larger scale, and showing the elevating gear and the traversing gear. Fig. 4 is a plan of the parts shown in

Fig. 3, with the gun and the casing of the recoil buffer and return springs removed and a portion of the trail broken away on one side. Fig. 5 is a vertical section taken approximately on the line 1—1 of Fig. 3. Fig. 6 is a longitudinal section of the recoil buffer and return spring casing; Fig. 7 is a cross section of the same taken on the line 2—2 of Fig. 6, and Fig. 8 is a sectional end view as seen from the right of Fig. 6. Fig. 9 is a view showing the relative position of the parts of the buffer piston when in the firing position. Fig. 10 is a view of the piston at the commencement of the recoil movement. Fig. 11 is a view of the buffer of the piston during the recoil. Fig. 12 is a view of the piston at the commencement of the return movement, and Fig. 13 shows the relative position of the parts during the return movement of the gun.

A is the gun.

B is the gun-cradle to which the gun is attached and with which it slides.

C is the trail.

D is the traversing bar or frame and D' D' are its trunnions.

E is the hand wheel of the elevating gear and F the hand wheel of the traversing gear.

G is the buffer and return spring casing provided with lateral guides g, g for the skids b, b of the gun-cradle B to slide upon. The said casing is supported in the traversing bar by the pivot D².

The gun is supported at its breech end by sliding blocks b' fitted to the skids b and is connected near its forward or muzzle end to a bracket b² also forming part of the skids b, said bracket being so situated that it does not overhang the end of the spring casing at any point of recoil. The skids b are firmly connected together at intervals by cross-pieces or transoms b³, as well as by the aforesaid bracket b² and by a cross-head b⁴ at the rear end of the skids; to this cross-head the buffer cylinder g^x is also firmly connected. The said elevating gear comprises two concentric or telescopic screws e', e² of which the outer one e² is carried by a stationary nut e³ mounted in an oscillatory bracket e⁴, and the inner one e' is coupled at its upper end to the elevating pin e⁵ which is carried by the aforesaid traversing bar or frame D. The outer

100

screw e^2 is revolved in the stationary nut by means of a bevel wheel e^6 carried by a tubular shaft or boss e^7 which surrounds the outer screw and has an internal feather e^8 engaging 5 with a corresponding longitudinal groove in the said outer screw. The outer screw and bevel wheel thus revolve together without impeding the longitudinal movement of the outer screw within the tubular shaft or 10 boss e^7 that carries the bevel wheel as is well understood. The outer screw therefore acts as a revolving nut with respect to the inner screw e' which is prevented from revolving by the elevating pin e^9 with which it engages 15 at its upper end as aforesaid. Motion is imparted to said bevel wheel e^6 from a shaft E' carried by bracket c on the trail, which shaft has at its outer end the hand wheel E for actuating it and at its inner end a bevel pinion 20 e^9 which transmits motion to the said bevel wheel e^6 as hereinafter explained.

The aforesaid elevating screws and the bevel wheel e^6 which drives them are carried by the aforesaid oscillatory bracket e^4 which 25 has hollow trunnions carried by appropriate pins or long bolts e^{10} projecting transversely toward each other from opposite sides of the trail to which they may be connected by detachable means. This oscillatory bracket e^4 30 thus permits the elevating screws to adapt themselves to the various inclinations their axes assume in changing the elevation of the gun. By reason of the oscillations of the said oscillatory bracket e^4 it will be obvious 35 that the aforesaid bevel pinion e^9 on the elevating shaft cannot be arranged to gear directly with the bevel wheel e^6 that actuates the outer elevating screw. We therefore interpose between said bevel pinion and 40 bevel wheel, an idle bevel wheel e^{11} (Figs. 3 and 5) which gears with both and is so situated that its axis of rotation is coincident with the axis of oscillation of the said bracket e^4 . In this manner the various 45 bevel wheels will always maintain their correct engagement, the inclination of their toothed peripheries converging to a common point.

The traversing gear comprises a screw F' 50 which engages with an internally threaded nut f provided with a prolongation f' terminating in an eye f^2 through which passes a corresponding lug g^2 on the buffer and spring casing G . The nut f slides, and the screw F' rotates in a box F^3 which is pivoted at F^4 to a bracket D^3 secured to the traversing bar or frame D . The traversing screw F' is provided with a collar F^5 , and an internally threaded cap F^6 is screwed upon the outer end of the box F^3 and thus cooperates with the outer end of the latter to prevent longitudinal movement of the traversing screw. The box F^3 is provided with a graduated scale F^7 (Fig. 4) which in conjunction with 65 an index arm or finger on the buffer and

spring casing G will serve to indicate the degree of traversing movement imparted to the gun by the actuation of the traversing gear.

The cylinder g^x of the recoil buffer is surrounded by the return springs g' which are 70 inclosed by the casing G as is well understood. The said buffer cylinder g^x is fitted with a shoulder g^2 at its front end, by means of which it acts as a compressor rod for the springs. At the rear end, the buffer cylinder 75 is in the form of a hollow screw g^3 passing through a sleeve nut g^4 , which has a shoulder g^5 to hold the springs in place on the buffer cylinder when the gun is dismantled for transport by mules. The sleeve-nut g^4 is 80 for the purpose of putting the initial compression on the springs. It is secured to the aforesaid cross-head b^4 by an interrupted screw and is prevented from turning by a spring pin g^6 (Fig. 1). The holes g^7 for filling 85 the buffer cylinder with liquid are at the rear end of the cylinder, thus the filling and also the initial compression of the springs may both be effected at the breech end of the gun. The holes g^7 are closed by means of plugs g^{7x} 90 as shown in Fig. 4.

The piston rod g^8 of the recoil buffer passes through a stuffing box and gland g^9 at the front end of the buffer cylinder, and is secured to a cap g^{10} which screws on to the front 95 end of the return spring case G with an interrupted thread, a spring catch g^{11} insuring that it always occupies the same position relatively to said spring case. The piston consists of three parts, g^{12} , g^{13} , g^{14} , one (91) 100 fixed to or formed solid with the piston rod, one (g^{13}) free to turn angularly on the rod, and one (g^{14}) free to move longitudinally 105 against the resistance of a spiral spring g^{15} on the rod. Each of said portions has ports g^{16} in its circumference, and the angularly movable part g^{13} has a projection which fits into a rifled groove which is formed in the cylinder. When in the firing position, the ports in the fixed part g^{12} and angularly 110 movable part g^{13} coincide, but are almost closed by the sliding part g^{14} as shown in Fig. 9. During the recoil of the gun and cradle the liquid passes through the ports in the 115 fixed and angularly movable parts, and forces back the sliding part until an opening sufficiently large for the escape of the liquid has been obtained. The angularly movable part g^{13} is also moved by the rifled groove and gradually closes the said opening by setting the ports out of coincidence and thus causes the buffer-piston to exert resistance to the recoil movement, such resistance varying with the stability of the carriage Figs. 10 120 and 11. On the return motion of the gun and cradle after recoil, the sliding part g^{14} of the piston is forced by its spring against the angularly movable part, which movement causes a gradual cut off of the flow of liquid 125 as the end of the return motion is being com- 130

pleted, thus permitting the return of the gun without shock Figs. 12 and 13. The said sliding part of the piston may have extra openings to facilitate the flow of the liquid past it.

We would here remark that we do not intend to include in our present claiming clauses the formation of a buffer piston with three ported-members of which one is angularly 10 displaceable during the recoil and return movements of the gun, as we have already disclosed such an arrangement. Neither do we intend to include telescopic screw elevating gear connected at its upper part with a 15 traversing bar or frame and at its lower part supported in an oscillatory bracket, as such an arrangement has also previously been disclosed by us.

What we claim and desire to secure by 20 Letters Patent of the United States is:—

1. In a gun carriage or mounting, the combination with the recoiling gun and the casing of the recoil buffer and return springs, of a pair of skids arranged one on each side of 25 said casing, guides on said casing for the skids to slide upon, a bracket on said skids for supporting the gun near its forward end or nozzle and so situated that it will not overhang the buffer and spring casing at any 30 point of recoil, means for connecting the breech end of the gun to said skids, transverse pieces or transoms for connecting the skids together, a sliding cylinder of the buffer and spring casing, means for connecting the 35 skids to said sliding cylinder, and means for supporting said casing in the carriage or mounting with a capability of lateral and vertical movements, substantially as described.

2. In a gun carriage or mounting, the combination with the recoiling gun and the casing of the recoil buffer and return springs, of means whereby the said gun is supported by and adapted to recoil on said casing, a traversing bar or frame trunnioned in the carriage or mounting, telescopic elevating screws pivotally connected respectively with the said bar or frame and the carriage or mounting, a nut engaging with the outer one of said telescopic screws, a bevel wheel on said nut with which gears an idle bevel wheel concentric with the pivotal connection of the telescopic screw with the carriage or mounting, a hand actuated spindle mounted on the carriage, a bevel pinion at the inner end of said spindle 50 gearing directly with said bevel wheel, a pivot depending from the casing of the recoil buffer and return springs and carried by the

traversing bar or frame, and means for moving said casing about the axis of its pivot for 60 traversing the gun, substantially as described.

3. In a gun carriage or mounting, the combination with the recoiling gun and the casing of the recoil buffer and return springs, of 65 means whereby the said gun is supported by and adapted to recoil on said casing, a traversing bar or frame trunnioned in the carriage or mounting, telescopic elevating screws of which the inner one is pivotally 70 connected by a detachable pin with the said bar or frame and the outer one is carried by an oscillatory bracket detachably connected with the carriage or mounting, a nut carried by said oscillatory bracket and engaging with 75 the outer screw, a bevel wheel on said nut with which gears an idle bevel wheel concentric with the axis of the oscillatory bracket, a hand actuated spindle mounted on the said carriage, a bevel wheel at the inner end of 80 said pinion gearing directly with said idle bevel wheel, a pivot depending from the casing of the recoil buffer and return springs and carried by the traversing bar or frame, and gearing for moving said casing about the 85 axis of its pivot for traversing the gun, substantially as described.

4. In a gun carriage or mounting, the combination with the recoiling gun and the casing of the recoil buffer and return springs, of 90 means whereby the said gun is supported by and adapted to recoil on said casing, means for supporting said casing with a capability of lateral and vertical movements in the carriage or mounting, a sliding cylinder for the 95 buffer and spring casing, a hollow screw attached within the rear end of the said sliding cylinder, return springs mounted upon said cylinder, a sleeve nut mounted on said hollow screw and adapted to be adjusted thereon for exerting the initial compression on the return springs, means for detachably connecting said sleeve nut with the gun, a shoulder upon the sleeve nut against which the return springs abut at the rear, and means for 100 preventing longitudinal movement of said shoulder substantially as described.

In testimony whereof we have hereunto set our hands in presence of two subscribing witnesses this eleventh day of September 110 1906.

ARTHUR TREVOR DAWSON.
